Primary Examiner — Joseph Kukella*Assistant Examiner* — Laron M. Amerson(74) *Attorney, Agent, or Firm* — MARSHALL,
GERSTEIN & BORUN LLP(57) **CLAIM**

The ornamental design for a vehicle control panel, as shown and described.

DESCRIPTION

1. Vehicle control panel

1.1 : Perspective

1.2 : Front

1.3 : Right

1.4 : Top

1.5 : Bottom

1.6 : Back

1.7 : Left

Vehicle control panel with rotary knob and 4 shortcut buttons for activating different functions. The vehicle control panel is controlled by rotating the rotary knob or by activating the shortcut buttons. The vehicle control panel is designed to be integrated into the vehicle's central dashboard or other appropriate area.

1 Claim, 7 Drawing Sheets(56)
